CLAIM

The ornamental design for a removable sole for spiked soles, as shown.

DESCRIPTION

FIG. 1 is a top plan view of a removable sole for spiked shoes showing my new design;

FIG. 2 is a bottom plan elevational view thereof;

FIG. 3 is a toe end elevational view thereof;

FIG. 4 is a heel end elevational view thereof;

FIG. 5 is a left side elevational view thereof;

FIG. 6 is a right side elevational view thereof;

FIG. 7 is a top plan view of a removable sole for spiked shoes showing an alternate form of my new design;

FIG. 8 is a bottom plan view of the alternate form thereof;

FIG. 9 is a toe end elevational view of the alternate form thereof;

FIG. 10 is a heel end elevational view of the alternate form thereof;

FIG. 11 is a left side elevational view of the alternate form thereof; and

FIG. 12 is a right side elevational view of the alternate form thereof.
